(57) **CLAIM**

The ornamental design for a control panel for inside a vehicle, as shown and described.

DESCRIPTION

FIG. 1 is a perspective view of a control panel for inside a vehicle showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is an enlarged perspective view showing area 8 taken from FIG. 1.

The broken lines illustrate portions of a control panel for inside a vehicle that form no part of the claimed design. The broken lines in FIGS. 1 and 8 illustrate boundaries of an enlarged view that form no part of the claimed design.
